HINGE

Edwin E. Slick, Pittsburgh, Pa.

Application March 4, 1937, Serial No. 128,977

6 Claims. (Cl. 16—135)

This invention pertains to hinges, and more particularly, to improved forms which are especially suitable for mounting the doors of vehicles.

Previous to the present invention, a number of problems have arisen in connection with the design and construction of hinges suitable for the doors of automobiles, trains, airplanes, etc. And, it has been an object of my invention to provide a new and improved form of hinge construction suitable for such utilization.

Another object has been to provide an improved form of hinge which permits a wide outward door swing and which is at least semi-concealed.

15 Another object of my invention has been to provide a streamlined type of hinge construction.

A further object has been to devise a simple, effective and efficient type of hinge construction which combines the advantages of a wide outward door swing and concealed and protected operating parts.

20 A still further object of my invention has been to provide a semi-concealed hinge construction having a high efficiency with respect to wind resistance.

25 These and many other objects of my invention will appear to those skilled in the art from the drawing, the specification, and the appended claims.

30 In the drawing:

Figure 1 is a top sectional view through a hinge constructed in accordance with my invention; this view shows the hinge in a mounted relationship with respect to a door post and a door, and by dotted lines shows the position of the hinge and door when the latter is opened;

Figure 2 is a top view, partially in section, showing a detail of the construction of Figure 1;

Figure 3 is a top sectional view similar to Figure 4 but showing a modified construction;

Figure 4 is a front side view in elevation of the construction shown in Figure 3;

Figure 5 is a view similar to Figure 2, showing a detail of the modified construction of Figure 4; and

Figure 6 is a view similar to Figure 4 showing a further modification.

As shown particularly in Figures 1 and 2, I provide a pair of shank members 10 and 12 that are mounted upon inner opposite edges or faces of door and frame members 15 and 16, respectively, and extend outwardly therefrom. Each of the shanks 10 and 12 has a flat planar foot or attaching portion which is suitably mounted upon the door 15 by screws or bolts 11, and has an

outwardly extending main body portion that forms an obtuse angle with respect to the attaching or foot portion and forms an acute angle with respect to the outer planar face of the door and post construction upon which it is mounted. 5 The extreme end of the shank 12 is provided, as shown, with a rounded knuckle having bearing portions adapted to receive a pintle pin 13.

As shown particularly in Figure 4, the pintle pin 13 is of ordinary construction and is mounted 10 to extend through opposite walls of a smooth, rectangular form of cover or box member 17 or 17'. The cover 17 preferably has at least three spaced-apart side walls, two of which are apertured to provide bearing portions that are complementary with the bearing portions of the bearing butt. The cover element 17' preferably has four spaced-apart enclosing side edges.

In the case of the embodiment of my invention shown in Figures 1 and 2, the shank member 10 itself provides the cover member 17, since it is rounded at its outer end to enclose the knuckle or pintle bearing of the shank 12 and is provided with upper and lower end closure pieces or sides 18, see particularly Figure 2. It will be 20 seen that a streamlined construction is provided and that the hinge joint portion is substantially hidden, enclosed, or concealed by the box-like shell 17 or 17' of the shank 10. Since the hinge construction has an acute angle with respect to the plane of the door, and preferably slopes gradually in the direction of air flow, see Figure 1, it is very efficient from an aerodynamic standpoint. The inclined face 17 of the outer and enclosing shank member 10 inclines outwardly in a 25 backward direction and has a smooth contour uninterrupted by breaks in the direction of the air stream flow. Air resistance is materially reduced.

In Figure 3, I have shown a modified form of hinge having a three-piece, as distinguished from the two-piece shank construction of the embodiment of Figures 1 and 2. In this construction, the hood or rectangular member is designated by the numeral 17', see Figure 4, and is securely fastened as by spot welding it to an outwardly-extending portion of the shank member 10', as at 40 19. Like the one-piece shank construction of 10 of the embodiment of Figure 1, the rear end of the member 17' is smoothly rounded back over the back face of the knuckle or hinge bearing portion of the inner shank 12. Since the cover element 17' is provided with both front and rear vertical sides, the construction will be efficient 45 from an aerodynamic standpoint, regardless of 50 55

the direction towards which the shanks 10' and 12 are mounted to extend; the cover is cup-like in appearance. Figure 4 shows the appearance of this construction from the outside of the vehicle.

The cover element 17', as shown, has a substantially uniform outer planar surface and permits the hinge to be mounted to extend in any suitable direction. In this construction, one portion of the cover 17' is spaced from a portion of the shank 10' to which it is attached. Since the three-part construction is more saving of materials, it may be preferable from a commercial standpoint over the two-piece type of Figures 1 and 2.

In Figure 6, the car body member 16 has been slightly concaved or counter-sunk to permit the end of the outer cover portion 17 of the hinge construction to project closer to the door surface to more completely enclose the hinge shank. When the door 15 is opened, the curved end of the element 17 can then enter the sunk portion without striking the body surface.

Although I prefer to construct the members of my invention from strip or strap plate metal material and to cold press or roll them into the desired shaped relationships, it will be apparent to those skilled in the art that many other suitable materials and methods may be employed in this connection.

Attention is called to the efficient action of the hinge construction as illustrated by the dotted lines of Figure 1. It is seen that the door 15 can be opened outwardly a considerable distance beyond the post 16 to give a maximum opening for persons entering and leaving the car. The construction is sturdy, strong, and effective, and will withstand the strains of an outward throw of the door much better than the old hinges of unsightly outline having a high resistance to the air stream flow. The hinge or pintle may be maintained in a thoroughly greased or oiled condition without splattering the car, because of the cover portion 17 or 17'.

In the preferred embodiment of my invention shown, for example, in Figures 3, 4, and 5, the shank portion 12 extends from an attaching plate or mount portion at one end thereof at an obtuse angle with respect thereto and terminates at its other end in a bearing portion. The outer shank element of the pair 10' has a planar body portion having a substantially right angular relationship with respect to one end portion thereof which may be termed the attaching plate or mount portion thereof. A cup-like member 17' has inwardly projecting wall portions adjacent opposite sides and ends thereof that are smoothly, integrally, and continuously connected to a substantially planar body portion thereof. As shown particularly in Figure 3, the body portion of the cover plate element 17' is adapted to extend substantially parallel to planar surface portions of the door construction when the door is in a closed position. The other or extending end of the body portion of the outer shank 10' is complementarily nested in the cup element 17' adjacent one end thereof; the cup-like element 17' extends therefrom and terminates in a pair of spaced-apart pintle bearing portions. The side and end walls of the cup-like element 17' preferably enclose both the extending portions of the inner shank 12 and of the outer shank 10' to minimize air resistance and to protect them from the elements.

Although I have shown and described certain

embodiments of my invention in the present application, it will appear to those skilled in the art that many additions, omissions, subtractions, modifications, and combinations thereof may be made without departing from the spirit and scope of my invention as indicated by the appended claims.

I claim:

1. In a hinge, a pair of shank elements, an attaching plate portion extending from one end of each of said elements and adapted to be mounted upon a suitable door and frame construction, a hinge bearing portion extending from another end of one of said shank elements, and an enclosing shank element receiving the other end of the other shank element of said pair and being secured thereto, said enclosing element having a portion extending beyond an extending end of said other shank element and having a bearing portion on such extending portion, said enclosing element substantially enclosing exposed portions of said pair of shank elements when the hinge is in a closed relationship, and a pintle engaging said hinge bearing portion of said first-mentioned shank and said bearing portion of said enclosing element for pivotally mounting said shank elements in position with respect to each other.

2. In a hinge, a pair of shank elements, each of said shank elements having an attaching plate portion and body portions extending angularly outwardly therefrom, said shank elements having an inner and outer relationship with respect to each other when mounted on a suitable door construction, the body portion of the inner of said shank elements terminating at its outer end in a hinge bearing, a cup-shaped enclosing element, the body portion and an extending end of the other of said shank elements being nested within said enclosing element and being secured thereto, said enclosing element substantially enclosing exposed portions of said pair of shank elements when the hinge is in a closed relationship, said enclosing element extending beyond the extending end of the body portion of said last-mentioned shank and terminating in a bearing portion, and means pivotally connecting the bearing portion of said enclosing element with the hinge bearing portion of said first-mentioned shank element.

3. In a hinge, a pair of shank elements, each shank element terminating at one end in an attaching plate portion, one of said attaching plate portions being adapted to be mounted on a door frame and the other of said attaching plate portions being adapted to be mounted upon a door, one of said shank elements having a body portion terminating in a hinge bearing portion, said body portion of said last-mentioned shank element extending outwardly at an angle with respect to said attaching plate portion thereof and beyond a door construction upon which it is adapted to be mounted, the second of said shank elements having a body portion extending outwardly at an angle with respect to its attaching plate portion and making an acute angle with respect to the body portion of said other shank element when said pair of shank elements are in a mounted position with respect to the door construction and the door construction is in a closed relationship, a cup-like enclosing element having side wall and end wall portions extending therefrom and being weld-connected to and extending beyond and providing a continuation of an outer end of the body portion of said second

shank element, said enclosing element being mounted over and receiving the body portion of said second-mentioned shank element within the confines of at least four wall portions thereof and being rigidly secured thereto, said enclosing element having a pair of spaced-apart bearing portions, and means pivotally connecting said spaced-apart bearing portions with said hinge bearing portion of said first-mentioned shank element.

4. In a hinge, a pair of shank elements, each shank element having an attaching plate portion adjacent one end thereof, said shanks having extending body portions having an inner-outer relationship with respect to each other when said shank elements are mounted on a suitable door structure, the inner of said shank elements having a body portion extending at an obtuse angle with respect to its attaching plate portion, the outer of said shanks having a shorter body portion extending at a right angle with respect to its attaching plate portion, said outer shank having a cup-like cover portion enclosing the said extending portions of said pair of shank elements, said cover portion having a planar outer surface extending substantially parallel to the door structure when the latter is in a closed relationship, said inner shank element and said cover portion having cooperating hinge bearing portions.

5. In a hinge, a pair of shank elements, each of said shank elements having an attaching plate portion adjacent one end thereof, said shank elements having body portions having an inner-outer relationship with respect to each other when said shank elements are mounted on a suit-

able door structure, the inner of said shanks having a body portion extending at an obtuse angle with respect to its attaching plate portion and terminating in a hinge bearing portion, the outer of said shanks having a body portion extending at a right angle with respect to its said attaching plate portion, the outer of said shanks having a shorter body portion and an enclosing element extending beyond and providing an offset continuation of an outer end of said shorter body portion, said enclosing element having continuous wall portions substantially enclosing its own extending body portion and the extending body portion of the other of said shank elements as well as said hinge bearing portion of said inner shank element.

6. In a hinge, a pair of shank elements, an attaching portion extending from one end of each of said elements and adapted to be mounted upon a suitable door and frame construction, a hinge portion extending from another end of one of said shank elements, and an enclosing shank element receiving the other end of the other shank element of said pair and being secured thereto, said enclosing element having a portion extending beyond an extending end of said other shank element and having a hinge portion on such extending portion, a hinge connection between the hinge portion of said first-mentioned shank element and the hinge portion of said enclosing element, said enclosing element substantially enclosing exposed portions of said pair of shank elements when the hinge is in a closed relationship.
